US0D1013730S

(12) **United States Design Patent** (10) Patent No.: **US D1,013,730 S**
(45) Date of Patent: ** Feb. 6, 2024

(54) **AIR COLLECTING DUCT FOR MACHINES**

(71) Applicant: **Bühler AG**, Uzwil (CH)

(72) Inventors: **Kevin Hausammann**, St. Gallen (CH);
Jürgen Moosmann, Berg (DE)

(73) Assignee: **Bühler AG**, Uzwil (CH)

(**) Term: **15 Years**

(21) Appl. No.: **35/514,457**

(22) Filed: **Dec. 15, 2021**

(80) **Hague Agreement Data**

Int. Filing Date: **Dec. 15, 2021**

Int. Reg. No.: **DM/220450**

Int. Reg. Date: **Dec. 15, 2021**

Int. Reg. Pub. Date: **Jun. 17, 2022**

(51) **LOC (14) Cl.** **15-99**

(52) **U.S. Cl.**

USPC **D15/5**

CPC **F02M 35/161** (2013.01)

(57) **CLAIM**

The ornamental design for air collecting ducts for machines, as shown and described.

DESCRIPTION

1. Air collecting duct for machines
- 1.1 : Perspective
- 1.2 : Back
- 1.3 : Front
- 1.4 : Bottom
- 1.5 : Top
- 1.6 : Left
- 1.7 : Right
